UNITED STATES PATENT OFFICE.

PIERPONT E. DUTCHER, OF UPPER MONTCLAIR, NEW JERSEY.

GOLF CLUB.

Application filed November 7, 1924. Serial No. 748,426.

To all whom it may concern:

Be it known that I, PIERPONT E. DUTCHER, a citizen of the United States, and resident of Upper Montclair, in the county of 5 Essex and State of New Jersey, have invented a new and useful Improvement in Golf Clubs, of which the following is a specification.

This invention relates to an improvement 10 in golf clubs, and, more particularly, in the head of the clubs which are especially designed for long distance driving.

An object of the invention is to provide 15 a golf club head which is so shaped as to offer a minimum of resistance to the air during that portion of the golfing swing in which the greatest acceleration of the club head should be obtained and is obtained in a correct swing.

20 Another object consists in providing a golf club head which is so shaped as to embody a stream-line form arranged in such angular relation with respect to the striking face of the club, that the axis of the 25 stream-line is quite nearly coincident with the direction of movement of the head of the club, considering both vertical and horizontal components during that part of the swing in which greatest acceleration of club 30 head speed should be obtained.

Another object consists in providing certain improvements in the form and construction of a golf club head whereby the above named and other objects may be effectively attained.

A practical embodiment of my invention is represented in the accompanying drawings, in which—

Fig. 1 represents a detail plan view of the 40 head and part of the handle.

Fig. 2 represents a section taken in the plane of the line II—II of Fig. 1.

Fig. 3 represents a detail front elevation of the club head and part of the shaft.

45 Fig. 4 represents a section taken in the plane of the line IV—IV of Fig. 3.

Fig. 5 represents a diagrammatic view, 50 partly dotted, showing different positions of the club during that portion of the swing in which greatest acceleration of the club head should be obtained.

Golf clubs used for long distance driving, such as driver, brassie, and spoon, commonly have comparatively large heads composed of wood, and it is an important con-

sideration that these heads shall be so shaped as to pass through the air, during the swing of the club preparatory to striking the ball, with a minimum of resistance.

The golf swing is difficult to illustrate and 60 difficult to describe in words, but there are certain fundamental factors which have almost universal approval among those well skilled in this pastime, and which may be observed by means of the slow motion pictures or by selecting individual views from a set of motion photographs.

It is common, at the present time, to photograph the most noted golf players and to 65 select a group of fifteen or twenty views 70 from the motion photographs so as to illustrate with clarity the position of the body, head, arms, hands, and club at various stages of the swing when properly and effectively performed. These pictorial representations 75 almost universally show that, in performing a stroke with the long distance clubs, the wrists are considerably bent at the top of the stroke, so that the club extends off at something like right angles to 80 the left arm, which is ordinarily quite straight. This bent position of the wrists and angular relationship of the club shaft and left arm are substantially maintained 85 during a large portion of the downward swing and, indeed, until the hands are approximately at the level of the waist. In other words, from the top of the swing down to this position, the club head is dragged or pulled with a sort of elliptical motion rather 90 than being swung with a true circular motion.

However, after the hands have reached 95 about the level of the waist, the wrists begin to straighten out so as to impart acceleration 95 and great speed to the head of the club immediately before and at the time of its impact with the ball. This is frequently referred to as the "flick" or "snap" of the wrists, and it is an essential of correct 100 timing of the stroke resulting in long distance driving in a straight path. Failure rapidly to accelerate the club head speed at this portion of the swing will not only result in a comparatively feeble blow being imparted to the ball, with the concomitant of a short flight, but will also frequently result in a poorly hit ball passing off at an angle to the intended line of flight.

105 It may also be noted that, during the por- 110

tion of the swing after the hands reach about the level of the waist, there are both vertical and lateral components in the direction of travel of the club head. In other words, the 5 club head is moving from a height down toward the ground and is also moving from a rearward position forwardly toward the ball.

My invention contemplates forming the 10 head of the club with a stream-line shape so disposed in angular relation to the striking face of the club head, as to impart the least resistance to the movement of the club head during the part of the swing above described in which greatest acceleration should be obtained.

Referring to the drawings, the club head in general is denoted by 1, and it may be secured in any well known or approved manner to a suitable shaft 2.

The striking face of the club head is marked 3 and an inset 4 of metal, vulcanized fiber, or other hard material, is provided at the lower portion of the striking face in 25 the customary manner.

From the striking face 3 rearwardly, the head is tapered to its back edge, which latter is drawn down quite finely, as well shown in Fig. 2.

30 The direction of this taper is preferably such that what I here choose to call the longitudinal axis of its vertical section, represented by dot and dash lines marked L—L in Fig. 1, extends at an obtuse angle away from a horizontal projection of the shaft 2. This assists in minimizing the resistance of the club head to the air during all that portion of the swing from the top down to a short distance previous to impact with the 40 ball, because during nearly all of this portion of the swing, the point of the heel, marked 5, precedes the remainder of the club head. This feature of construction and the reason therefor is set forth in my co-pending application for United States Patent Serial No. 661,607, filed September 8, 1923, wherein a club head having a more exaggerated form in this respect is illustrated.

50 In the invention which forms the subject matter of the present application, the said longitudinal axis of the vertical section of the club head projects upwardly at an acute angle to the striking face 3, as is well indicated by dot and dash lines in Fig. 2. This is a feature of prime importance because, during practically all of that portion of the swing which takes place after the hands reach about the level of the waist, the club head is moving downwardly toward the ground so that, if the bottom of the club were substantially flat, it would provide a broad surface contacting with the air and lying in a plane at a pronounced angle to 60 the arc of movement. By having a stream-

line form so related to the plane of the striking face that its said axis projects upwardly at an acute angle to said face, a stream-line form is imparted to the club head which eliminates the flat surface contact of the club 70 with the air just described and thereby greatly facilitates the acceleration of the club head as against the air resistance encountered in traversing downwardly the vertical component of that portion of the 75 swing after the hands reach about the level of the waist.

This portion of the swing which has several times been mentioned above is diagrammatically represented in Fig. 5, by full and dotted line positions of the club. In this figure, the point marked C is the center of the arc through which the club head travels, and said point C is intended to represent, substantially, the wrists of the player. The straightening of the wrists from their bent position, above described, moves the club head throughout the arc which is represented in dot and dash lines and marked A, A, and, during this period, there is practically no movement of the arms. In other words, the club pivots around the wrists of the player while there is almost complete stoppage of the swinging movement of the arms, and it will be seen that this results in very great acceleration in the speed of movement 90 of the club head so that it may strike the ball with best effect.

As pointed out above, the shape of the club head which forms the subject matter of this invention is best calculated to decrease air resistance during this portion of the swing, and I believe that it is most important for the air resistance to be minimized at this time if the stroke is to be most effective.

It is true that, during that portion of the swing immediately preceding contact of the club head with the ball, the stream-line arrangement of my present invention is not such as to be coincident with the direction 100 of movement of the club head, and, therefore, the beneficial effect of my invention is lost, at least in part, at this moment. Nevertheless, this is not a matter of major importance because the speed of movement 110 of the club head has been so greatly accelerated during the portion of the stroke represented in Fig. 5 of the drawings, in which portion the stream-line arrangement according to my invention is used to great benefit, that the speed will not be appreciably reduced because of any imperfection in the stream-line arrangement immediately preceding contact with the ball, especially as the last named portion of the stroke is very 120 short when compared with that portion of the stroke during which my invention comes fully into play.

The most important feature, then, of my present invention resides in forming the 130

stream-line club head in such a manner that what I have designated as the longitudinal axis of its vertical section extends upwardly at an acute angle to the striking face of the 5 club. This arrangement, in combination with the obtuse angularity of said axis with respect to a horizontal projection of the shaft, makes a stream-line form which is most effective in minimizing air resistance 10 throughout the swing as a whole; but I wish to point out that the vital characteristic of my present invention will be embodied so long as the said longitudinal axis of the vertical section extends upwardly at an acute 15 angle to the striking face of the club, even though the said axis does not lie in an obtuse angle relationship to a horizontal projection of the shaft.

I prefer also to make the neck 6 of the 20 club head stream-line in form, as represented by the section shown in Fig. 4, since this portion of the head is also somewhat bulky, and a stream-line effect is advantageous.

It will be understood that various changes 25 may be resorted to in the form and construction of the various parts without departing from the spirit and scope of my invention; and hence, I do not intend to be limited to the details herein shown and described, except as they may be included in the claims.

What I claim is:

1. A golf club head having a striking face, said head being provided with a body portion extending rearwardly from said face, 35 said body portion being rearwardly tapered to constitute a stream-line form, the longitudinal axis of the vertical section of said tapered portion extending upwardly at an

acute angle to the plane of said striking face. 40

2. A golf club head having a striking face, said head being provided with a body portion extending rearwardly from said face, said body portion being rearwardly tapered to constitute a stream-line form, the longitudinal axis of the vertical section of said tapered portion extending upwardly at an acute angle to the plane of said striking face and at an obtuse angle away from a horizontal projection of the shaft. 45 50

3. A golf club head having a striking face, said head being provided with a body portion extending rearwardly from said face, said body portion being rearwardly tapered to constitute a stream-line form, the longitudinal axis of the vertical section of said tapered portion extending upwardly at an acute angle to the plane of said striking face, said head also having a neck of stream-line form in cross section. 55 60

4. A golf club head having a striking face, said head being provided with a body portion extending rearwardly from said face, said body portion being rearwardly tapered to constitute a stream-line form, the longitudinal axis of the vertical section of said tapered portion extending upwardly at an acute angle to the plane of said striking face and at an obtuse angle away from a horizontal projection of the shaft, said head 70 also having a neck of stream-line form in cross section. 65

In testimony, that I claim the foregoing as my invention, I have signed my name this 5th day of November, 1924.

PIERPONT E. DUTCHER.
